UNITED STATES PATENT OFFICE.

GEORGE BERNERT AND JACOB BERNERT, OF SOUTH GERMANTOWN, WISCONSIN.

PNEUMATIC ELEVATOR.

977,849.

Specification of Letters Patent.

Patented Dec. 6, 1910.

Application filed May 13, 1910. Serial No. 561,201.

To all whom it may concern:

Be it known that we, GEORGE BERNERT and JACOB BERNERT, both citizens of the United States, and residents of South Germantown, 5 in the county of Washington and State of Wisconsin, have invented certain new and useful Improvements in Pneumatic Elevators; and we do hereby declare that the following is a full, clear, and exact description thereof.

Our invention has for its object to provide a simple, economical and powerful pneumatic elevator, the construction and arrangement being such that the product to be elevated is delivered to the air blast tube through a valve-controlled branch in such manner that the air blast from the fan is not interrupted or broken incidental to opening of the valve for delivering the product 20 into said air blast tube or conveyer trunk.

With the above objects in view the invention consists in certain peculiarities of construction and combination of parts to be set forth hereinafter with reference to the 25 accompanying drawings and subsequently claimed.

In the drawings Figure 1 represents a sectional elevation of a pneumatic elevator apparatus embodying the features of our invention, the section being indicated by line 1-1 of Fig. 3; Fig. 2, a detail cross-section of one of the fans employed in our apparatus, as indicated by line 2-2 of Fig. 1; Fig. 3, a sectional front elevation of the apparatus as indicated by line 3-3 of Fig. 4; Fig. 4, a plan view of the same with parts broken away and in section, and Fig. 5, a detail sectional elevation of another form of our improved valve for delivering grain or 40 other products directly into the conveyer trunk.

Referring by characters to the drawings, 1, 1, represent casings of oppositely disposed fans 2, which fans are mounted upon a common shaft 3 that is journaled in pillow blocks 4 at its opposite ends, the ends being extended through the fan casings. Power from any suitable source is imparted to the fan-shaft 3 through a pulley 5 in belt connection with said source. These fans form no part of our invention and are of standard type, their casings being provided with air inlet apertures 6, that encircle the fan shaft and the usual tangentially disposed discharge trunks 7. The discharge trunks 7 are connected by branch pipes 8 to a com-

mon delivery pipe 9, as clearly shown in Fig. 1, it being understood that by utilizing a pair of fans connected in this manner to a common delivery pipe that the efficiency is 60 proportionately greater than in the case where a single fan is utilized although, in some instances, it may be desirable to use the pneumatic elevator in connection with a single fan.

Each discharge trunk is provided with a grain receiving aperture 10 and surrounding this aperture is a box 11, which is secured to the upper trunk wall. As best illustrated in Fig. 1, this box is provided with an inwardly opening valve plate 13 in hinge connection therewith, the said flap valve being held in its closed position by means of a suitable spring.

Secured to the mouth of the box 11 directly over the valve, is an open mouthed tubular trough 14, in which is mounted a shaft 15 carrying a spiral conveyer section 16, the conveyer section terminating at a point over the mouth of the trough which 70 communicates with the valve-controlled box 11. The inner end of the trough 14 is provided with an upwardly extending receiving mouth 17, to which mouth is secured a grain delivery hopper 18.

It should be understood that each discharge trunk 7 is provided with a trough 14 as just described, and a corresponding mechanism, the troughs being extended toward each other and terminating so as to form a space between their receiving mouths 17, while the hopper 18 is provided with spout 80 openings that connect each mouth.

The shaft 15 that carries the spiral conveyer section extends across the machine through each trough 14 and, being provided with spiral conveyers pitched in opposite directions, will cause grain to be delivered to the discharge trunk 7 of each fan. In order to reduce or back gear the speed of the spiral conveyers from the high speed fan shaft, we provide a counter-shaft 19, which counter-shaft extends through the receiving mouths 17 of each trough, being journaled in brackets 20 secured to the inner walls of said mouths, as shown in Figs. 4 and 3. The counter-shaft receives its motion from a pair of small pulleys 21, carried by the fan shaft, which pulleys are in belt connection with large pulleys 22 upon opposite ends of the counter-shaft. Motion from the counter-shaft is imparted to the spiral worm

conveyer shaft 15 through small and large pulleys 23, 24, respectively, in belt connection with each other, the pulley 24 being fast upon the shaft 15 and, as shown, being provided with another face 24^a, which is adapted to operate in conjunction with another face 23^a of the counter-shaft pulley, the second set of faces being so proportioned as to reduce the speed of the shaft 15 still further 10 should the belt connection be slipped from the first set to said second set, it being understood that this belt is of such length with relation to the proportion of the two sets of pulley faces that it is capable of fitting 15 either.

In the operation of our device grain or other products to be conveyed are delivered to the hopper 18. The right and left spiral conveyers within their respective troughs 20 force the delivered grain toward the boxes 11 and as the grain becomes packed within the trough over the valves 12, the said valves will yield downwardly and permit the grain to be forced into the discharge trunks 7. 25 Thus said valves are not open except when the ends of the troughs 14 directly over the valve boxes are filled, and hence the air current from the blast fans cannot escape through the valve-controlled opening that 30 delivers grain to said troughs. The force of the air blast is thus maintained at a constant pressure and grain or other product desired to be conveyed may be delivered at great 35 distances, it being understood that the grain which is caught up by the air blast is forced up through the branch pipes 8 and united at a common delivery pipe 9, from which pipe it may be spouted to any desired point.

Fig. 5 illustrates a portion of an air trunk 40 7^a provided with a grain receiving aperture 10^a, over which is fitted a circular housing 14^a. This housing contains a rotary valve 12^a, which valve is mounted upon a driven shaft 15^a and is provided with a series of 45 compartments formed by radial valve wings. In this instance grain is delivered between the valve pockets from above and, as the valve slowly rotates in the direction of the arrow, these pockets discharge the grain into 50 the trunk 7^a. The empty pockets upon their return to the grain receiving end of the housing may be vented of any air contained therein through an aperture 25 that is formed in the circular walls of the housing. 55 Thus it will be seen by this arrangement that the edges of the valve-blades revolving within the circular housing will form a closure which will prevent air from being taken into the trunk as the grain is de-

livered, or, even though no grain were passing through the valve, an air seal is thus maintained. By this arrangement the same result is accomplished as that in connection with the mechanism shown in Fig. 1, in which latter case it will be seen that when there is no grain within the trough, or not a sufficient quantity to warrant delivery, the valve-plate 12 is held closed, the spring being of sufficient strength to hold said valve closed in opposition to the suction of air 70 within the discharge trunk.

We claim:

1. A pneumatic elevator comprising a pair of fan casings having apertured air discharge trunks extending therefrom, a drive shaft extending through both fan casings, fans mounted upon the drive shaft within the casings, valve boxes secured to the discharge trunks about their apertures, spring-controlled flap valves mounted within the 80 boxes, a grain hopper located between the valve casings, troughs connecting the grain hopper and each valve box, a shaft extending through the troughs, right and left spiral conveyers mounted in the opposite troughs 85 respectively, driving means connecting the conveyer shaft and fan driving shaft, a grain delivery pipe, and branch pipes connecting the grain delivery pipe and fan casings 90 trunks.

2. A pneumatic elevator comprising a pair of fan casings having apertured air discharge trunks extending therefrom, a drive shaft extending through both fan casings, fans mounted upon the drive shaft within the casings, valve boxes secured to the discharge trunks about their apertures, valves mounted within the boxes, a grain hopper located between the valve casings, troughs connecting the grain hopper and each valve box, a shaft extending through the troughs, right and left spiral conveyers mounted in the opposite troughs 100 respectively, driving means connecting the conveyer shaft and fan driving shaft, a grain delivery pipe, and branch pipes connecting the grain delivery pipe and fan casings 105 trunks.

In testimony that we claim the foregoing we have hereunto set our hands at Menomonee Falls in the county of Waukesha and 110 State of Wisconsin in the presence of two witnesses.

GEORGE BERNERT.
JACOB BERNERT.
